(57) **CLAIM**

The ornamental design for a lid for a weatherproof sportsman's trunk as shown and described.

DESCRIPTION

FIG. 1 is a top perspective view of a lid for a weatherproof sportsman's trunk;

FIG. 2 is a bottom perspective view of the lid for a weatherproof sportsman's trunk shown in FIG. 1;

FIG. 3 is a top plan view thereof;

FIG. 4 is a bottom plan view thereof;

FIG. 5 is a right side elevational view thereof; and,

FIG. 6 is a front side elevational view thereof.

A left side elevational view is not shown because it is a mirror image of the right side elevational view shown in FIG. 5. A rear side elevational view is not shown because it is a mirror image of the front side elevational view shown in FIG. 6.

1 Claim, 5 Drawing Sheets
